UNITED STATES PATENT OFFICE.

LABAN J. EVEREST, OF GRAND RAPIDS, MICHIGAN, ASSIGNOR TO SAMUEL D. YOUNG, OF GRAND RAPIDS, MICHIGAN.

SHOW-CASE.

SPECIFICATION forming part of Letters Patent No. 767,805, dated August 16, 1904.

Application filed December 10, 1903. Serial No. 184,672. (No model.)

To all whom it may concern:

Be it known that I, LABAN J. EVEREST, a citizen of the United States, residing at Grand Rapids, in the county of Kent and State of Michigan, have invented new and useful Improvements in Show-Cases, of which the following is a specification.

This invention relates to the class of showcases termed "all-glass" show-cases and aims 10 to set up a glass show-case in which the glass plates forming the top, front, and sides of the case are secured together through the medium of metallic fasteners without making any apertures through the plates.

15 The invention further aims to construct an all-glass show-case which can be readily set up, taken apart, and packed in compact form for shipment.

20 The invention further aims to construct an all-glass show-case which shall be simple in its construction, strong, durable, efficient in its use, and comparatively inexpensive to set up.

25 With the foregoing and other objects in view the invention consists of the novel combination and arrangement of parts hereinafter more specifically described, illustrated in the accompanying drawings, and particularly pointed out in the claims hereunto appended.

30 In describing the invention in detail reference is had to the accompanying drawings, forming a part of this specification, wherein like reference characters denote corresponding parts throughout the several views, and 35 in which—

Figure 1 illustrates a perspective view of a show-case constructed in accordance with this invention. Fig. 2 is a top plan view of one front corner of the show-case, showing one of 40 the combined coupling and clamping devices for the side and front plates. Fig. 3 is a perspective of one of the sections of the combined coupling and clamping device. Fig. 4 is a perspective of another of the sections of the 45 combined coupling and clamping device. Fig. 5 is a like view of another of the sections of the combined coupling and clamping device. Fig. 6 is a perspective of the coupling-sections of the combined coupling and clamping

device assembled. Fig. 7 is a perspective 50 view of a portion of one of the side plates. Fig. 8 is a perspective view of one of the side coupling devices employed for the top and side plates. Fig. 9 is a perspective view of a portion of one of the side plates having 55 mounted thereon a side coupling device. Fig. 10 is a perspective view of one of the rear coupling devices. Fig. 11 is perspective, partly broken away, of the rear of the case, showing the arrangement of one of the rear 60 coupling devices. Fig. 12 is a perspective view of a corner fastening device for the side plates. Fig. 13 is a sectional plan of one of the rear corners of the case, showing the arrangement of the fastening device. Fig. 14 65 is a sectional plan of one of the front corners of the case; and Fig. 15 is a perspective view of one of the lower front corners of the case, showing the fastening devices for the side and front plates at the lower corners thereof. 70

Referring to the drawings by reference characters, 1 denotes the side plates, which are formed of glass, and each of said plates has its top edge at a point removed from its forward end provided with a countersunk portion 2 75 and below said countersunk portion 2 provided with a pair of recesses 3. Each of the plates 1, below its top edge at a point nearer the forward end thereof than the point in which is formed the recesses 3, is provided with additional recesses 4, the purpose of which will be hereinafter referred to. Each of the plates 1 has its forward edge cut away a suitable distance, so as to form a shoulder 5 at a point removed from the top edge thereof, and the 85 function of said shoulder 5 will be hereinafter referred to.

The combined coupling and clamping devices for the front upper corners of the case are each formed of three sections, which are 90 designated by the reference characters A, B, and C. The section A is termed a "side-plate-coupling section" and is employed for coupling the side plate 1 to the front plate at the upper corner thereof. The section A is constructed of a pair of sides and a front wall, (designated by the reference characters 6, 7, and 8, respectively.) The side and front walls 95

are formed integral with each other, and each of the side walls 6 7 is provided with an opening 9, and the top edge of the front wall 8 is formed with a seat 10.

5 The section A is adapted to be mounted upon the shoulder 5 of its respective side plate and is of such height as to be flush with the top edge of the plate and so that the side walls 6 7 thereof extend parallel with the faces of the side plate.

The section B is termed a "front-plate-coupling section" and is constructed of a pair of side walls 11 12 and the end wall 13. Each of the side walls 11 12 is provided with an opening 14, and the side wall 12 at its top is formed with an outwardly-extending protuberance 15, which is adapted to engage in the seat 10, so that the section A and the section B will be coupled together. The side walls 11 and 12, 20 wall 13, and protuberance 15 of the section B are formed integral with each other.

Two combined coupling and clamping devices are employed, and the sections A of the said devices are adapted to inclose the forward edge at the forward upper corner of each of the side plates, and the sections B of the said devices are adapted to inclose the side edges of the front plate at the forward upper corners thereof.

30 The openings 14 in the sections B are adapted to register with the recesses 17 in the front plate, so as to receive a suitable soldering or cementing medium 19, Fig. 14, for securing the sections B to the plate 18.

35 The clamping-sections C of the combined coupling and clamping devices are each substantially L-shaped in contour and have each end thereof provided with an inwardly-extending binding-flange 20.

40 When the sections A and B are arranged in position for coupling the side plates to the front plate, the openings 9 in the sections A are adapted to register with the recesses 4 in the side plates 1, so that a suitable soldering 45 or cementing medium 16 can enter through the openings 9 and into the recesses 4 and secure said sections A to the side plates. The clamping-section C is provided with an opening 19', which registers with the outer opening 9 of each of the sections A, so that the cementing or soldering medium 16 will extend through said opening 19'.

When the combined coupling and clamping devices are in position, the clamping-sections 55 C thereof are adapted to have the flanges 20 thereof engage the vertically-extending edge of the side wall 7 of the section A and the vertically-extending edge of the side wall 11 of the sections B. By employing the combined coupling and clamping devices constructed in the manner as set forth and arranged in the manner as set forth the side plates 1 are securely coupled and clamped to the front plate 18.

Each of the side coupling devices for coupling the side plates to the top plate of the case

is designated by the reference character D, and each of said couplings D is an integral body having two pairs of outwardly-extending arms 21, each arm of each pair provided with an opening 22 and formed integral at 70 their upper ends with a top plate 23, adapted to be seated in the countersunk portion 2 of the plate 1, and said top plate 23 has projecting upwardly therefrom an inverted-L-shaped holding-arm 24, forming a groove adapted to 75 receive the top plate D' of the case. The openings 22 and the arms 21 are adapted to register with the recesses 3 in the plate 1, and a suitable soldering or cementing medium is placed within the recesses 3 and the openings 80 22, as indicated by the reference characters 22'. Each of the coupling devices D when in position is adapted to have the upper face of its top plate 23 flush with the upper edge of the side plate upon which the coupling device 85 D is mounted, and the top plate D' is adapted to rest upon the top edge of the side plates 1 and upon the upper face of the top plate 23, and the side edge of the top plate D' abuts against the inverted-L-shaped holding-arm 90 24, and by such arrangement the top plate D' of the case is retained in position and coupled to the side plates 1.

The rear of the show-case is preferably provided with two posts H and a cross-rail H', 95 constructed in the ordinary manner, and the rear of the case may be provided with doors, if desired.

For the purpose of connecting the top plate D' a pair of coupling devices E is provided, 100 and each of said coupling devices E consists of a U-shaped member formed of top, bottom, and end walls 25, 26, and 27, respectively, and to the end wall 27 a rearwardly-projecting holding-arm 28 is provided. The top and bottom walls 25 26 are provided with an opening 29, which registers with recesses formed in the top plate D', and said recesses and openings 29 receive a suitable soldering or cementing medium, so as to secure the coupling devices E to the top plate D'. The rearwardly-extending holding-arm 26 is apertured, as at 105 30, and through said apertures extends a suitable holdfast device for connecting the coupling E to the cross-rail H'. (See Fig. 11.) 110

For the purpose of securing the rear upper corner of the side plates 1 to the post H a pair of fastening devices F are employed. (See Fig. 12.) Each of the fastening devices F consists of a U-shaped section 31, carrying 115 a rear plate 32, which is of such width as to form a pair of laterally-extending flanges 33. The U-shaped section of the fastener F is provided with openings 34 to receive a suitable holdfast device for securing said fastener F 120 to the posts H. The fasteners F are mounted in the posts H in a vertical manner and are in alignment with a suitable groove formed in the post, which receives the inner end of the side plates 1. 125

The reference character 35 denotes the base or bottom of the show-case, and at the forward corners thereof in its upper face a pair of fastening devices G G' is secured. Said 5 fastening devices G G' are provided with the seats 36 for the bottom portion of the front and side plates, as shown in Fig. 1, the fastening devices being shown more clearly in Fig. 15. The fastening devices G G' are each provided with openings 37, through which a suitable holdfast medium can extend, so the front and side plates can be secured to the fasteners G G'. It may be stated that in the upper face of the bottom 35 grooves are provided to receive the side and front plates of the case. 10 15

From the foregoing construction of show-case it is evident that what is termed an "all-glass" show-case is set up without providing the top, side, and front plates with openings 20 therethrough to receive holdfast devices and that the top, side, and front plates can be securely connected together by removable coupling, clamping, and fastening devices, and that when occasion requires the case can be readily 25 taken apart and reassembled.

It is thought that the many advantages of an all-glass show-case constructed in accordance with this invention can be readily understood from the foregoing description, taken in connection 30 with the accompanying drawings, and it will, furthermore, be evident that changes, variations, and modifications can be resorted to without departing from the spirit of the invention or sacrificing any of its advantages, 35 and I therefore do not wish to restrict myself to the details of construction hereinbefore described and as set forth in the annexed drawings, but reserve the right to make such changes, variations, and modifications as come 40 properly within the scope of the protection prayed.

Having thus fully described my invention, what I claim as new, and desire to secure by Letters Patent, is—

45 1. In a show-case, the combination with the front, side and top plates thereof, of means detachably connected with the side plates and engaging with the top plate for detachably connecting the top plates to the side plates, coupling-sections secured to the side plates, coupling-sections secured to the front plates, said coupling-sections of the front plate adapted to detachably engage with the coupling-sections of the side plates for detachably connecting 50 the side plates to the front plates, and clamping-sections engaging said coupling-sections for binding said coupling-sections together.

2. In a show-case, the combination with the front, side and top plates thereof, of means detachably connected with the side plates and engaging with the top plate for detachably connecting the top plates to the side plates, coupling-sections removably secured to the side plates, coupling-sections removably secured to 60 the front plates, said coupling-sections of the

front plate adapted to detachably engage with the coupling-sections of the side plates for detachably connecting the side plates to the front plates, and clamping-sections engaging said coupling-sections for binding said coupling-sections together. 70

3. In a show-case having its side, front and top of glass, the combination with the top, front and side plates, of means inclosing the upper corners of the side and front plates and detachably engaging with each other for detachably connecting the side and end plates together, and means carried by the side plates and adapted to receive the top plate for detachably connecting the top plate to the side. 75 80

4. In a show-case having its ends, side and top of glass, the combination with the front, sides and top plates, of combined coupling and clamping devices removably inclosing the upper corners of the front and side plates for detachably connecting said front and side plates together, and coupling devices detachably secured to the side plates and adapted to receive the top plate for connecting the top plate with 90 the side plates. 85

5. In a show-case having its front, sides and top all glass, the combination with the side glass plates provided with depressions, off-coupling devices mounted upon said side glass 95 plates and provided with openings registering with said depressions, and a suitable plastic binding medium extending through said openings and in said depressions for securing the coupling devices to the side plates. 100

6. A show-case comprising front, side and top plates of glass and a suitable rear wall, coupling-sections carried by the front plate, coupling-sections carried by the side plates and adapted to detachably receive the coupling sections of the front plate, thereby detachably connecting the side plates with the front plates, coupling devices carried by the side plates and adapted to receive the top plate for detachably connecting the top plate 110 to the side plates, fastening devices secured to the rear wall and attached to the top plate for connecting the top plate to the back plate, and corner-fastening devices carried by the rear wall for the side plates. 115

7. A show-case comprising front, side and top plates of glass and a suitable rear wall, coupling-sections carried by the front plate, coupling-sections carried by the side plates and adapted to detachably receive the coupling-sections of the front plate, thereby detachably connecting the side plates with the front plates, coupling devices carried by the side plates and adapted to receive the top plate for detachably connecting the top plate 120 to the side plates, fastening devices secured to the rear wall and attached to the top plate for connecting the top plate to the back plate, corner-fastening devices carried by the rear wall for the side plates, and a clamping-section. 125 130

tion adapted to engage with the coupling-sections of the side and front plates for binding said sections together.

8. A show-case comprising front, side and top plates of glass and a suitable rear wall, coupling-sections carried by the front plate, coupling-sections carried by the side plates and adapted to detachably receive the coupling-sections of the front plate, thereby detachably connecting the side plates with the front plates, coupling devices carried by the side plates and adapted to receive the top plate for detachably connecting the top plate to the side plates, fastening devices secured 15 to the rear wall and attached to the top plate for connecting the top plate to the back plate, corner-fastening devices carried by the rear wall of the side plates, a base for the said plates, and corner-fastening devices carried by the 20 base for the front and side plates.

9. A show-case comprising front, side and top plates of glass and a suitable rear wall, coupling-sections carried by the front plate, coupling-sections carried by the side plates 25 and adapted to detachably receive the coupling-sections of the front plate, thereby detachably connecting the side plates with the front plates, coupling devices carried by the side plates and adapted to receive the top plate 30 for detachably connecting the top plate to the side plates, fastening devices secured to the rear wall and attached to the top plate for connecting the top plate to the back plate, corner-fastening devices carried by the rear wall 35 for the side plates, a clamping-section adapted to engage with the coupling-sections of the side and front plates for binding said sections together, a base for the said plates, and corner-fastening devices carried by the base for 40 the front and side plates.

10. A show-case having a transparent front plate, transparent shouldered side plates, a transparent top plate, a removable coupling-

section mounted upon a shoulder on each of the side plates, each of said sections provided 45 with a seat, and a coupling-section attached to each end of the front plate and provided with a protuberance adapted to engage in said seat for detachably connecting the front and side plates together.

11. A show-case having a transparent front plate, transparent shouldered side plates, a transparent top plate, a removable coupling-section mounted upon a shoulder on each of the side plates, each of said sections provided 55 with a seat, a coupling-section attached to each end of the front plate and provided with a protuberance adapted to engage in said seat for detachably connecting the front and side plates together, and coupling devices mounted upon 60 the side plates and adapted to receive the top plate for detachably connecting the top plate to the side plates.

12. A show-case having a transparent front plate, transparent shouldered side plates, a 65 transparent top plate, a removable coupling-section mounted upon a shoulder on each of the side plates, each of said sections provided with a seat, a coupling-section attached to each end of the front plate and provided with a protuberance adapted to engage in said seat for 70 detachably connecting the front and side plates together, coupling devices mounted upon the side plates and adapted to receive the top plate for detachably connecting the top plate to the 75 side plates, corner-fastening devices for said side plates, corner-fastening devices for said side and front plates, and fastening devices for said top plate.

In testimony whereof I have hereunto set 80 my hand, in presence of two subscribing witnesses, this 3d day of December, 1903.

LABAN J. EVEREST.
